(57) CLAIM

I claim, the ornamental design for a bag, as shown and described.

DESCRIPTION

FIG. 1 is a perspective view of a bag, showing my new design;

FIG. 2 is a front view thereof;

FIG. 3 is a rear view thereof;

FIG. 4 is a side view thereof;

FIG. 5 is an opposite side view thereof;

FIG. 6 is a top view thereof; and,

FIG. 7 is a bottom view thereof.

The connected dashed lines used in the drawings indicate stitching and form a part of the claimed design.
